VARA L. PACE, OF BEAUMONT, TEXAS.

PLAYER PIANO.

1,405,152.

Specification of Letters Patent. Patented Jan. 31, 1922.

Application filed December 29, 1919. Serial No. 347,987.

To all whom it may concern:

Be it known that I, VARA L. PACE, a citizen of the United States, residing at Beaumont, in the county of Jefferson, State 5 of Texas, have invented certain new and useful Improvements in Player Pianos; and I do hereby declare the following to be a full, clear, and exact description of the invention, such as will enable others skilled 10 in the art to which it appertains to make and use the same.

This invention relates to mechanical pianos whose action is operated by pneumatic mechanisms; and the objects of the 15 same are to improve such mechanisms.

The invention comprises a new form of valve which is self-centering and does away with the guide pin usually employed, and an amplification of the wippen so that the 20 striker rod is placed at the front of the pneumatic mechanism where it is accessible and the change in leverage permits the use of a smaller pneumatic.

Details are set forth below and shown in 25 the drawings in which:

Figure 1 is a general sectional view of this invention applied to a piano player.

Figure 2 is a sectional detail showing the 30 improved valve canted out of its usual vertical position and yet closed against the upper valve seat.

The parts of the piano player mechanism are too well known to need a detailed description here, and I will therefore refer 35 only to such as are concerned with the point which the invention seeks to improve. The vacuum chamber 1 has a valve-lifting diaphragm 2 at the bottom and an opening at the top directly above this diaphragm.

40 The opening 3 is enlarged at 4 and then again reduced at 5, this construction being effected by forming the mechanism of a combination of laminæ superposed and bored and channeled to produce the openings 45 and channel required, there being sheets 20 and 21 of material suitable for valve seats, interposed between the laminæ and through which are formed openings as illustrated that register with the openings 3 and

50 5 and are of the same diameter as the latter. Beneath the enlargement 4 is the lower valve seat, and above the enlargement the upper valve seat, while a channel 6 leads laterally from the enlargement to the pneumatic 55 7, and it is the closing action of the latter which actuates the wippen and causes

the hammer to strike the wire. In order that this action may take place successfully, it is necessary that when the rise of the diaphragm lifts the valve off of its lower 60 seat it shall reliably close it against the upper seat to prevent the admission of air to the pneumatic, while simultaneously connecting the vacuum chamber with the pneumatic to close the latter and strike the wire. 65 Heretofore it has been found that the valve which moves between these two seats often becomes displaced or canted slightly, so that while it may be retained usually on the lower seat by the suction created in the 70 vacuum chamber, it is not always reliably closed against the upper seat when raised by the diaphragm—hence it has been usual and is yet customary in many pneumatic mechanisms to guide this valve in its vertical 75 movement. My present invention is designed to do away with the guide, which naturally simplifies mechanism and renders the valve more easily removable when the parts are to be disconnected.

80 One feature of my invention consists in constructing the valve itself in a peculiar manner, as perhaps best seen in Figure 2. The numeral 10 designates the stem of this valve, and 11 is its foot standing directly 85 over the cushion at the center of the diaphragm. 12 is the head of the valve which is usually round and of larger diameter than the foot although of smaller diameter than the enlarged portion 4 in which it 90 stands. The upper face of this head I preferably form slightly convex as seen at 13, and this face will fit accurately against the upper valve seat 14, even if the stem is canted as seen in Figure 2. The lower face of 95 the head may be flat, and this will lie upon the lower valve seat 15 against which it is drawn by suction. The head is slightly smaller than the enlargement 4, which permits the valve to have some little lateral 100 play, and yet I find that it will never become displaced to such an extent as to leak.

Another point of my invention is that the wippen 18 has a considerable extension 19 which is carried forward completely over 105 and above the pneumatic mechanism, and the striker rod 17 leads upward from the pneumatic 7 to a point beneath the forward end of this extension 19 so that as the pneumatic is collapsed the extension is raised 110 and the wippen is actuated to cause the hammer to strike a string or wire. The

leverage produced by extending the wippen permits me to use a smaller pneumatic mechanism than usual, and with a small mechanism leakage would be fatal to the successful operation and therefore the improved valve above described becomes a practical necessity.

What is claimed as new is:

- 10 The combination with a plurality of superimposed laminae having valve seat material between them and having alining openings therethrough of which the opening of the intermediate lamina is of larger diameter than the remaining openings, said intermediate lamina having a channel communicating with its opening, the valve seat material extending over the upper and lower walls of the enlarged opening to constitute
- 15

valve seats and having openings there-through registering with and of the same 20 diameter as the minor openings, of a valve comprising a relatively thin disk head within the enlarged opening and having a diameter greater than that of the opening through either valve seat material, the head 25 having one face spheri-sectional and having its other face flat, and a stem projecting from the flat face of the head and coaxial with the extension of the axis of the head.

In testimony whereof, I affix my signature in the presence of two witnesses.

VARA L. PACE.
